US00D771113S

(12) **United States Design Patent** (10) **Patent No.:** **US D771,113 S**
(45) **Date of Patent:** ** *Nov. 8, 2016

(54) **DISPLAY SCREEN OR PORTION THEREOF WITH GRAPHICAL USER INTERFACE**

(71) Applicant: **Samsung Electronics Co., Ltd.**, Suwon-si (KR)

(72) Inventors: **Ho-Ik Hwang**, Hwaseong-si (KR); **Dae-Hong Ki**, Suwon-si (KR); **Jun-Ho Choi**, Seoul (KR)

(73) Assignee: **SAMSUNG ELECTRONICS CO., LTD.**, Suwon-Si (KR)

(*) Notice: This patent is subject to a terminal disclaimer.

(**) Term: **14 Years**

(21) Appl. No.: **29/513,742**

(22) Filed: **Jan. 5, 2015**

(30) **Foreign Application Priority Data**

Aug. 28, 2014 (KR) 30-2014-0041989

(57) **CLAIM**

The ornamental design for a display screen or portion thereof with graphical user interface, as shown and described.

DESCRIPTION

FIG. 1 is a front perspective view of a display screen or portion thereof with graphical user interface showing our new design;

FIG. 2 is a front view thereof;

FIG. 3 is a top view thereof; and,

FIG. 4 is a front perspective view thereof, showing additional unclaimed environment.

The dashed broken lines showing portions of the display screen or portion thereof with graphical user interface are for environmental purposes only and form no part of the claimed design.

1 Claim, 4 Drawing Sheets
